UNITED STATES PATENT OFFICE.

ANDREW S. FISHER, OF ALTOONA, PENNSYLVANIA.

MARGINAL PROTECTOR AND GUARD FOR DESK PADS OR BLOTTERS.

1,357,971.

Specification of Letters Patent.

Patented Nov. 9, 1920.

Application filed March 1, 1919. Serial No. 280,008.

To all whom it may concern:

Be it known that I, ANDREW S. FISHER, citizen of the United States, residing at Altoona, in the county of Blair and State 5 of Pennsylvania, have invented certain new and useful Improvements in Marginal Protectors and Guards for Desk Pads or Blotters, of which the following is a specification.

10 This invention relates to an improved marginal guard and protector for desk pads, blotters, and the like, and has as its primary object to provide a device of this character which may be readily applied to pads 15 and blotters as now in use for protecting and covering the side margins and edges of the blotter or pad so as to prevent wear thereon as well as obviate the common unsightliness of said edges.

20 The invention has as a further object to provide a device of this character which will be yieldably held in place upon the pad or blotter so that, when desired, the device may be readily removed and wherein 25 the presence of the guard and protector upon the pad or blotter will not interfere with the normal use thereof.

The invention has as a still further object to provide a guard and protector 30 which, when used in connection with a pad having a stiff body, will tend to prevent warping thereof.

And a further object of the invention is to provide a device which will prevent pencils or the like from rolling off of a pad, while the device may carry a measuring 35 scale as well as suitable advertising matter and will thus provide an attractive advertising novelty.

40 Other and incidental objects will appear hereinafter. In the drawings:

Figure 1 is a perspective view showing a conventional type of pad and blotter equipped with a pair of my improved devices,

45 Fig. 2 is a transverse sectional view taken on the line 2—2 of Fig. 1 and looking in the direction of the arrows,

Fig. 3 is a plan view showing a conventional type of pad and blotter having one 50 of my improved devices arranged at each margin thereof, and

55 Fig. 4 is a fragmentary perspective view showing the manner in which the guard and protector is formed at its ends for engagement beneath the corner pockets of a pad.

In order that the construction and manner of use of my improved device may be accurately understood I have, in the drawings, shown the device in connection with 60 a conventional type of flexible desk pad 10 having the usual leather corner pockets 11, a blotter 12 being shown upon the pad and engaged at its corners in these pockets. The device of the present invention is preferably 65 formed from a single piece of suitable resilient material and includes a flat elongated body 13 which, as particularly shown in Fig. 4 of the drawings, is preferably formed with rounded terminal edges. At its inner 70 margin the body is provided with an oblique forwardly and downwardly directed flange 14 extending from end to end of the body and formed on the body at its outer edge is a downwardly directed guard flange 15. 75 This latter flange extends throughout the major portion of the length of the body and is disposed at substantially right angles thereto. At the ends of the flange 15, the body is cut away corresponding to the thickness of said flange and is thus formed with slightly reduced end portions 16 having their outer edges flush with the inner face of the flange. As will be seen, a device constructed as just described may be readily 80 stamped at one operation from a piece of suitable resilient sheet metal. However, if desired, the device may, of course, be formed of celluloid, fiber or other approved material and may be embossed, colored or 85 enameled to match the colors of a standard pad or blotter.

In Fig. 1 I have shown a pair of the devices in position upon the pad 10 at the front and rear margins thereof. In applying the guard and protector, the flange 15 thereof is presented outwardly when the device is laid flat against the blotter 12 and its reduced end portions 16 engaged beneath the pockets 11 at corresponding corners of 100 the pad. The device is then shifted outwardly until the flange 15 engages, in the manner shown in Fig. 2, over the adjacent side edges of the blotter and pad when the terminals 16 of the device will be received 105 within said pockets abutting at their outer edges with the corresponding outer side portions of the pockets. These terminals will thus coact with the pockets for holding the device against outward movement while the flange 15 will coact with the adjacent edges of the pad and blotter for holding 110

the device against inward movement. Furthermore, it is to be noted, as particularly shown in Fig. 2, that the end portions of the flange 14 within the pockets will, by their upward bulge within the pockets, serve to tension the pockets over the end portions 16 of the device. This tensioning of the pockets will, in turn, result in causing the pockets to clamp the device against the blotter 12 so that the flange 14 will be yieldably held to contact throughout its entire length with the blotter. The device will thus be firmly held in place while a closed joint between the free edge of the flange 14 and blotter will be maintained so that dirt or other foreign matter cannot collect beneath the device. As will be readily understood, a pair of the devices may, as shown in Fig. 1, be employed, or, if desired, one 20 of the devices may, as illustrated in Fig. 3, be used at each margin of the pad and blotter. In this figure I have conventionally shown the pad at 17, this pad being substantially identical with the pad 10 and carrying a blotter 18.

It will thus be seen that I provide a particularly simple and effective device for the purpose set forth. When used upon a pad or blotter, the device will, as will now be clear, not only protect the margins of the pad or blotter against wear but the flange 15 of the device will, in each instance, also cover one side edge of the blotter or pad so as to obviate the common unsightly appearance of said edges. Furthermore, when the device is used in connection with the type of pad employing a stiff body, the device will, as will also now be clear, tend to prevent warping of the pad body. Also, as will be seen, the device will prevent pencils or other round objects from rolling off a pad and, as shown in the drawings, a measuring scale may be imprinted or otherwise arranged upon the flange 14 of the de-

vice to thus further enhance its usefulness. 45 Advertising matter may also be arranged upon the body 13 of the device and in this way the device may be employed as a means of placing an advertisement of a permanent character constantly before the user 50 and his patrons.

Having thus described the invention, what is claimed as new is:

1. A device of the character described including an elongated guard strip provided at one side margin thereof with a depending guard flange terminating short of the ends of the strip to define pocket entering portions at the end portions of the strip. 55

2. A device of the character described including an elongated strip body provided at its inner margin with a flange to contact the upper face of a pad and provided at its outer margin with a depending guard flange terminating short of the ends of the 60 body to define pocket entering portions at the end portions of the body.

3. A device of the character described including an elongated strip body provided at its inner margin with a flange to contact 70 the upper face of a pad and provided at its outer margin with a depending guard flange terminating short of the ends of the body to define pocket entering portions, the first flange being disposed at an angle with 75 respect to the strip body to bear upwardly beneath pad pockets engaged by the entering portions for clamping the free edge of such flange against the pad.

4. As a new article of manufacture, a 80 protector and guard for desk pads or the like including an elongated guard strip provided at its outer edge with a depending stop flange and at its end portions with reduced pad pocket entering members. 85

In testimony whereof I affix my signature.

ANDREW S. FISHER. [L. S.]
